(57) **CLAIM**

The ornamental design for a portion of a display screen with graphical user interface, as shown and described.

DESCRIPTION

FIG. 1 is a front view of an image of a portion of a display screen with graphical user interface according to a first embodiment thereof; and,

FIG. 2 is a front view of a second image thereof.

The appearance of the image transitions sequentially in between the images shown in FIGS. 1-2. The process or period in which an image transitions to another forms no part of the claimed design.

The broken line showings of portions of a display screen and text in the figures are environmental only and form no part of the claimed design.
